[57] CLAIM

The ornamental design for a movable platen for an injection molding machine, as shown and described.

DESCRIPTION

FIG. 1 is a front view of a movable platen for an injection molding machine showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a cross-sectional view thereof taken along the line 7—7 of FIG. 5;

FIG. 8 is a cross-sectional view thereof taken along the line 8—8 of FIG. 5;

FIG. 9 is a front perspective view; and,

FIG. 10 is a rear perspective view thereof.
